ROBERT BERRYMAN, OF PHILADELPHIA, PENNSYLVANIA.

Letters Patent No. 99,234, dated January 25, 1870.

LOW-WATER INDICATOR AND FEED-WATER REGULATOR.

The Schedule referred to in these Letters Patent and making part of the same.

To all whom it may concern:

Be it known that I, ROBERT BERRYMAN, of Philadelphia, Pennsylvania, have invented an Improved Low-Water Alarm and Feed-Water Regulator for Steam-Boilers, of which the following is a specification.

Nature and Object of the Invention.

My invention consists of an apparatus, fully described hereafter, whereby the admission of water to a steam-boiler is automatically regulated, and an alarm is given when the water in the boiler falls to a determined point.

Description of the Accompanying Drawings.

Figure 1, Sheet No. 1, is an elevation of my improved apparatus, showing the same applied to a steam-boiler;

Figure 2, Sheet No. 2, a sectional elevation of the apparatus, looking in the direction of the arrow, fig. 1; and

Figure 3, a side view, showing a modification.

Figure 4, Sheet No. 3, a view showing one mode of arranging the apparatus, so as to regulate the admission of water to the boiler.

General Description.

A is a vessel, which is, in the present instance, of a spherical form, and to the under side of which is secured a pipe, P, extending longitudinally to a point where it is bent at right angles, and passes through the shell of the boiler, within which it terminates at a point below the low-water line O.

At the upper end of the chamber is a pipe, P¹, to a branch on which is secured the pipe P², the latter extending horizontally to a point where it is bent at right angles, from which point it is carried downward through, and is secured to the shell of the boiler, the pipe terminating within the boiler at the low-water line. The portions of the pipe P and pipe P² on the outside of the boiler, should be of sufficient length to permit them to yield, in the manner described hereafter.

A lever, L, having its fulcrum on a projection, F, of a standard, D, resting on the shell of the boiler, is provided at one end with a weight, B, the opposite end being forked, so as to receive V-shaped projections on the pipe P¹, the lever and its weight thus supporting the vessel A and its adjuncts, and serving as a counterbalance for the same.

The lever R of the whistle W, extends through a rod, G, which is so secured to another rod, attached to the standard D, that it can be adjusted vertically, for a purpose described hereafter.

The whistle has an internal spindle terminating below in a valve, which is maintained in contact with its seat with a spring at the upper end of the spindle, the latter being connected to the above-mentioned lever R.

As long as the water in the boiler remains at its proper level, (that is, above the low-water line O, the ends of the pipes P and P² being consequently immersed in the water,) the pressure of steam will maintain the pipes and the vessel A full of water, so that the vessel will be depressed, its weight being in excess of the force exerted by the counterbalance lever L.

While in this depressed condition, the whistle-lever R, which passes through the stationary rod G, will be elevated, and will consequently permit the valve of the whistle to remain in contact with its seat.

When the water in the boiler becomes too low, however, that is, below the line O, the steam will enter the pipe P², and the vessel A will be speedily emptied of its water, and thus, becoming lighter, will, together with its whistle, be elevated by the counterbalance-lever L, and the lever R, which will also be elevated, (being controlled by the stationary rod G,) will cause the valve of the whistle to be opened, and an alarm to be given.

When the apparatus is to be used for regulating the admission of water to the boiler, the vessel A (or the lever L) is connected to a valve in the feed-water pipe, or with devices which control the action of the pump or the flow of the feed-water, so that when the vessel rises, the water will pass into the boiler, the descent of the vessel causing the water to cease its flow.

One mode of effecting this result is shown in fig. 4, when the lever L is connected, by a rod, J, with a lever operating a valve in the feed-water pipe.

The pipe P² is larger in diameter than the pipe P, so that the increased volume of steam, thus admitted to the vessel, will insure the instant and rapid discharge of the water from the same, and from the pipe P, and the prompt action of the apparatus.

In the modification illustrated in fig. 3, the whistle, instead of communicating with the vessel A, is stationary upon and communicates with the boiler, and is operated on the movement of the vessel or of its lever.

Although I have referred to flexible pipes P, P², it will be apparent that rigid pipes may be employed, steam-tight joints or couplings being placed in the pipes, at such points as may be necessary to allow the pipes to accommodate themselves to the movements of the vessel.

I do not here claim, broadly, the use of two pipes of different diameters, in connection with a vessel communicating with a steam-boiler; nor do I here claim

the combination of such pipes with the steam-whistle, as these features form the subjects of a separate application for Letters Patent; but

I claim—

1. The vessel A, or its equivalent, in combination with flexible or jointed pipes P and P², of different diameters, connected to the boiler, and forming communications between the said vessel and the water-space of the boiler, the whole operating in conjunction with the weighted lever L, or its equivalent, as a medium for giving an alarm, or regulating the flow of the feed-water, substantially as set forth.

2. The said vessel, in combination with a steam-whistle, and with the within-described devices for operating the whistle.

3. The rod G, adjustable in respect to the lever R, for the purpose described.

In testimony whereof, I have hereunto signed my name, in the presence of two subscribing witnesses.

ROBERT BERRYMAN.
